SUPPORTING STAND FOR GYMNASTIC BALANCE BEAM

George P. Nissen and Lawrence H. Conover, Cedar
Rapids, Iowa, assignors to Nissen Corporation, Cedar
Rapids, Iowa

Filed Nov. 1, 1961, Ser. No. 67,338

Term of patent 14 years

(Cl. D34—5)

FIGURE 1 is a perspective view of the supporting stand for a gymnastic balance beam embodying our new design; and

FIGURE 2 is a top plan view of the apparatus; and
FIGURE 3 is an enlarged end elevational view of the apparatus.

The broken line showing of a balance beam is for illustrative purposes only.

We claim:

The ornamental design for the supporting stand for gymnastic balance beam, as shown and described.
